UNITED STATES PATENT OFFICE.

JOHN MARTIN WELCH, OF BROOKLYN, NEW YORK, ASSIGNOR, BY MESNE ASSIGNMENTS, TO ROLAND T. PARKER AND CHARLES L. MOREAU, BOTH OF NEW YORK, N. Y.

RAZOR-BLADE SHARPENER.

Application filed September 13, 1921. Serial No. 500,321.

To all whom it may concern:

Be it known that I, JOHN MARTIN WELCH, a citizen of Canada, residing at Brooklyn, N. Y., have invented certain new and useful 5 Improvements in Razor-Blade Sharpeners, of which the following is a specification.

This invention relates to the sharpening of razor blades or other similar edged tools. The object of the invention is to devise a 10 simple and cheap means for sharpening razor blades and yet one that is very efficient. To that end I have made this invention which consists essentially in the passing over a glass surface of the bevelled edge of the 15 blade to be sharpened and the invention includes means for holding the blades in the necessary position.

It is to be understood that no abrasion of the blade takes place when being rubbed on 20 the glass, and the soap acts as a lubricant between the glass and the blade.

It is thought that the microscopic teeth of the blade are lined up in this operation, which therefor sharpens the blade without 25 abrading action.

I have illustrated one embodiment of my invention which is the best form of which I am at present informed but it is to be taken in an illustrative sense and not in a limiting 30 one for the invention is capable of different embodiments without departing from the spirit and scope of the invention. That the chosen embodiment may be clearly understood, I have illustrated it in the accompanying 35 drawings in which—

Figure 1 is a perspective view of my sharpener;

Figure 2 is a plan view of a double edged razor blade in position on the base of my 40 sharpener with the top of the sharpener removed;

Figure 3 is a plan view of the sharpener with a blade in place;

Figure 4 is an end view of the device;

45 Figure 5 shows how the bevelled edge of the blade is rubbed against the glass; and

Figure 6 shows the device as applied to a single edged razor blade.

My invention is really based upon the discovery that razor blades will be easily sharpened when rubbed over a glass surface in the presence of soap. As mirrors are always necessary for the act of shaving, the

sharpening medium is therefore always present so my invention includes the provision of a holder for a razor blade to hold the blade in such a position that one of its bevelled edges will lie flat against the glass and then the blade is rubbed over the glass. The sharpness which results is really surprising.

In the drawings, 11 indicates the glass which, of course, may either be glass or a mirror as just described. The holder comprises a base plate 12 having lugs 13 and 14 extending upwardly therefrom, together with a threaded stem 15. Upon this base plate is provided a curved top 16 having apertures therethrough 17, 18 and 19 adapted to register respectively with lugs 13, 14 and 15. A cap 20 or nut is provided which is adapted to screw onto the stem 15 to hold the parts in adjusted position. To apply the blade to the holder, the parts are disassembled. If the blade is of the doubled 75 edged type, it is dropped onto the base part 12 of the holder as shown in Figure 2 wherein the blade is numbered 21. Then the top part 16 of the holder is applied so that its concave face is nearest the glass and the cap 80 20 screwed into position to bend the blade as shown in Fig. 4 until one bevel 22 of each of its edges lies flat against the glass, whereupon the holder, with its blade is moved or rubbed over the glass, soap suds or lather 85 having preferably first been applied to the glass. The rubbing of the blade over the glass may be in any direction such as circularly but I find that in general, the best results are obtained by rubbing the blade 90 back and forth in a longitudinal direction.

Where the blade is of the single edged type, the back of the blade is held between the bottom plate 12 and the top 16 as shown in Fig. 6 and the rubbing action is carried 95 out as previously described.

The holder is so small that it can be carried unobtrusively in any container for the razor and with the holder bright nickel plated, it is very attractive and "matches" 100 the razor in both design and appearance. This method of sharpening a razor blade is surprisingly effective and only one bevel of each edge needs to be sharpened if the operator is careful to shave with the sharpened 105 bevel against his face.

What I claim is:

1. A method of re-aligning the microscopic teeth of a razor blade, which includes the step of rubbing said blade on glass without abrasion.
2. The method of claim 1, with the step of first applying to the glass an abrasion preventing medium.

3. A method of realigning the microscopic teeth of a razor blade without abrasion 10 which includes the step of rubbing said blade on polished glass.

In testimony whereof I have affixed my signature to this specification.

JOHN MARTIN WELCH.
